UNITED STATES PATENT OFFICE.

EDUARD FÄRBER, OF HEIDELBERG, GERMANY, ASSIGNOR TO THE INTERNATIONAL SUGAR AND ALCOHOL COMPANY LIMITED, A BRITISH COMPANY, LONDON, ENGLAND.

MANUFACTURE OF SUGAR.

No Drawing. Application filed June 15, 1925, Serial No. 37,329, and in Germany June 26, 1924.

As is well known it is possible to produce sugar from cellulose-containing material by means of concentrated hydrochloric acid, which for the sake of brevity will herein-
5 after be referred to as "wood-sugar". This sugar is a kind that has not yet been defined exactly, but amongst other things proves to be a complex sugar by reason of the fact that hydrolysis is necessary to convert it into a fermentable sugar.
10

Hitherto it has not been possible in a satisfactory manner to purify this complex sugar, i. e., to free it from acid and other detrimental accompanying substances. Ex-
15 periments by electrolysis, dialysis, and other methods have not led to a technical result. It was also not to be expected that it would be possible for this purpose to use alkaline earths, similar to the methods known for
20 cane sugar. Wood sugar being, as stated, a kind of sugar that hitherto has not been examined chemically, it was not even to be presumed whether it would in fact pass into an insoluble compound with alkaline earth
25 oxides. By reason of the sensitiveness of this sugar towards alkalies it was further to be feared that considerable losses would be incurred by the alkali action.

In a surprising manner it has, however,
30 been found that with alkaline earths it is possible to obtain a precipitation and puri-
fication of the wood-sugar by keeping within determined conditions. For this purpose it is necessary to introduce finely divided
35 calcium oxide into the strong sugar solution in the cold. The separated sugar-lime compound is filtered off and, suspended in water, is decomposed by acids which form insoluble lime salts.
40

For example the preferably 20-30% sugar solution after neutralization, which is prefer-
45 ably effected by means of calcium car-
bonate, is stirred up, at a temperature below
20° C., with finely powdered or finely dis-
persed calcium oxide. After a short time
there separates a copious precipitate of sugar-lime compound. After pressing and
washing with as small quantities of water as possible the moist compound is decom-
50 posed by acids, such as carbonic acid or sul-
phurous acid.

In this manner there are obtained very pure solutions of polysaccharides without any considerable losses. If the operation

were carried out by the methods known in 55 the cane sugar industry at higher tempera-
tures, then a very large portion of the sugar would be damaged or destroyed.

Instead of calcium oxide it is also possible to use strontium or barium oxide.
60

In order to convert the pure polysaccha-
rides or even the wood-sugar itself, thus ob-
tained, into fermentable sugar, it is neces-
sary to effect a splitting up into the simple
kinds of sugar. According to the present 65 invention this is effected by introducing wa-
ter into the molecule of the compound, that
is to say it is hydrolyzed. Mineral acid is
used as catalyst. The hydrolysis must be
effected under very special conditions. The 70 sugar is so sensitive to the action of acid at
high temperatures that it is only possible to
conduct the hydrolysis satisfactorily within
very narrow limits of sugar and acid con-
centration, time and temperature. Even 75
with very slight variations of the conditions
considered as being favorable, the sugar is
easily damaged or destroyed on the one hand
and is not completely hydrolyzed on the
other hand.
80

It is not absolutely necessary for the lime
precipitation described to precede the hy-
drolysis as by hydrolysis itself a partial pre-
liminary purification takes place at the same
time by subsidiary reaction. The hydroly-
sis takes place at various temperatures ei-
ther at ordinary or increased pressure. The
selection of the kind or conditions of heat-
ing depends essentially on the nature of the
original substance.
85
90

If a syrup is under consideration, which
has still a relatively high content of acid,
the procedure for example is as follows: The
syrup is dissolved in water in such a man-
ner that the concentration of syrup amounts 95
to about 20% and hydrochloric acid about
3%, then it is allowed to boil under ordinary
pressure for about 2-2½ hours.

If however a great bulk of material, freed
from acid, is available or if a neutral sugar
solution has been obtained by previous treat-
ment with lime, then hydrolysis is effected
under an excess pressure in order that a
minimum of acid will suffice. The solution
to be hydrolyzed is then so adjusted that it
100 contains 40% sugar and 0.3% hydrochloric
acid.
105

When operating according to the first ex-

ample under ordinary pressure then not more than 25% sugar and 3% hydrochloric acid must be present in the solution as otherwise damage or destruction of the sugar and simultaneously reverions take place. The duration of boiling depends on the content of sugar and acid of the solutions. The concentration of sugar is chosen as high as possible in view of the further treatment of the 10 solution which is necessary later on.

When operating under pressure according to the second example, the concentration may be at 40% and even higher, the acid content being below 1%, preferably 0.3%, 15 in order to enable the operation to be carried out in large metal vessels. Also in this case the duration and degree of heating depend on the content of the solutions. About 130° C. may be regarded as the upper temperature 20 limit.

By such hydrolytic dissociations the wood-sugar not only becomes directly fermentable but also crystallizable. In order to obtain crystal sugar from the hydrolyzed 25 solutions, it is necessary first to reduce the acidity to the point of neutral reaction and then to rapidly evaporate up to a degree of concentration suitable for crystallization. If there still existed an acid reaction the evaporation could not be effected without loss 30 and reconversion of the sugar, and even in the case of a neutral reaction it is advantageous to effect the evaporation as quickly as possible.

35 A fermentable wood-sugar solution prepared in accordance with one of the two hydrolyzing processes is neutralized, for example, by carbonate of sodium. In a vacuum evaporation or even in a roll drier, such, 40 for example as used for drying potatoes, wherein the material to be dried is run over a hot rotating roll on which it remains for only a part of a revolution, a syrup is produced therefrom, from which the separated 45 chloride of sodium is removed while hot. If then the syrup has a concentration of 70-80

per cent by weight of sugar, it is allowed to cool and crystallize out.

It is surprising that from the solutions obtained from a number of kinds of sugar 50 it is possible to obtain in this manner sugar in the form of crystals.

What I claim and desire to secure by Letters Patent of the United States is:—

1. A method for the production of pure, 55 fermentable, and crystallizable sugar from wood sugar, comprising, introducing a finely subdivided alkaline earth oxide into a strong, raw, wood sugar solution, separating out the resulting sugar-alkaline earth 60 compounds, then liberating the polysaccharides from the separated sugar-alkaline earth compounds by means of acid, which form insoluble alkaline-earth metal and then hydrolyzing the thus purified wood 65 sugar solution.

2. A method for the production of pure, fermentable, and crystallizable sugar from wood sugar, comprising, introducing finely subdivided calcium oxide into a strong wood 70 sugar solution while keeping the temperature below 20° C., then liberating the polysaccharides from the resulting sugar-calcium oxide compound by carbonic acid, and then hydrolyzing the thus purified wood sugar solution. 75

3. A method according to claim 1, wherein in the purified wood sugar solution is hydrolyzed by heating a solution thereof containing about 40% of sugar, and an acid content 80 up to about 1%, to about 130° C.

4. A method according to claim 1, wherein in the preliminarily purified wood sugar solution is hydrolyzed by heating a solution containing 40% of sugar and an acid content of 0.3%, up to 130° C. 85

5. A method according to claim 1, wherein in the purified and hydrolyzed sugar solution is exactly neutralized, and is then evaporated rapidly to a degree of concentration 90 suitable for crystallization.

EDUARD FÄRBER.
